UNITED STATES PATENT OFFICE.

JOSEPH L. DOSTAL, OF DETROIT, MICHIGAN, ASSIGNOR TO EARL HOLLEY, OF DETROIT, MICHIGAN.

METAL MOLD.

Application filed August 3, 1925. Serial No. 47,725.

To all whom it may concern:

Be it known that I, JOSEPH L. DOSTAL, a citizen of the United States, residing at 8530 Dexter Blvd., Detroit, in the county of Wayne and State of Michigan, have invented certain new and useful Improvements in Metal Molds, of which the following is a specification.

The object of this invention is to provide means whereby a metal mold of the type disclosed in the U. S. patent to Phillips, #1,099,997, will produce improved castings. The defect of castings produced in the said Phillips molds is that there is a tendency for the iron to leak through the joints between the two molds.

Figure 1 shows the mold in elevation.

Figure 2 shows a cross sectional plan view on the plane 2-2 of Figure 1.

The mold, for illustration, is shown adapted for the casting of pistons, and corresponds to the type of mold shown in the patent to Meloche #1,502,861.

The mold consists of two halves A and B,

and a facing joint C surrounding a core cavity D in which a core E is suspended and located concentrically therein. The joint C is milled off so that the two halves of the mold come together on a relatively narrow face, for the same purpose as that described in the Phillips patent referred to above, namely for the purpose of preventing or minimizing the leakage of iron between the molds during the casting operation.

A groove F forms a moat or dyke around the mold cavity D into which any iron which leaks past the joint C is caught, and where it will congeal to prevent further leakage of iron. The groove F also divides the joint C into two relatively narrow strips.

What I claim is:

A metal mold, comprising a cavity, a facing rib surrounding said cavity, a groove dividing said facing rib into two relatively narrow strips separated by said groove.

In testimony whereof I affix my signature.

JOSEPH L. DOSTAL.
